Apparatus for digging, plowing, or otherwise breaking up rock, shale, or conglomerate deposits upon the earth's surface, comprising a heavy metal frame including spaced vertical posts, a rearwardly projecting arm on the upper end of each post, a lower cross-member connecting the lower ends of the posts, and an upper cross-member connecting the upper ends of the posts, the upper ends of the posts being connected to the upper end of the upper cross-member.

2. The apparatus of claim 1, in which the upper cross-member is provided with a rearwardly projecting arm on its upper end, and the lower ends of the posts are connected to the lower end of the upper cross-member, and the upper ends of the posts are connected to the upper end of the upper cross-member.

UNITED STATES PATENT OFFICE

2,517,426

ROCK GOUGE

Charles P. Hall, Lindsay, Okla.

Application September 11, 1947, Serial No. 773,447

2 Claims. (Cl. 262—8)

1

The present invention relates to apparatus for gouging, plowing, or otherwise breaking up rock, shale, or conglomerate deposits upon the earth's surface.

In digging basements, in excavating for oil field slush pits, and the like, comparatively thin layers of rock, shale and the like are often encountered upon or near the earth's surface. Removal of such deposits is expensive, when it is necessary to break them with hand tools or dynamite.

The prime object of the present invention is to provide a heavy gouge or plow which may be powered by a usual motor driven tractor, and which is capable of loosening or breaking out in layers many of such deposits.

Another object is to provide a gouge of this class which is so arranged that downward thrust thereon may be applied by hydraulic rams.

A further object is to provide an apparatus in which the gouging bits may be easily and quickly removed for replacement.

An additional object is to provide an apparatus which will withstand the rough usage required by such operations.

Other objects will be apparent from the following description when taken in conjunction with the accompanying three sheets of drawings, wherein:

Figure 1 is a perspective view of the device operatively installed upon the rear end of a conventional tractor, the tractor being shown in dotted lines, and the device being depicted in raised position;

Figure 2 is a similar view showing the device in its lowered position; and,

Figure 3 is a perspective view, looking from the front, of the rock gouging element.

Like characters of reference designate like parts in those figures of the drawings in which they occur.

In the drawings:

The reference numeral 1 indicates, as a whole, the rear portion of a conventional motor driven tractor.

In carrying the present invention into being, the tractor 1 is equipped with a heavy metal frame including spaced vertical posts 2 and 3, each of which is equipped with a rearwardly projecting arm 4 on its upper end. The lower ends of the post are connected by a suitable cross-member 5 and their upper ends are similarly connected by a cross-member 6. The posts and cross-members are supported on the tractor chassis frame, not shown, and the upper ends of the

posts are held against swaying movement, by suitable braces 7 and 8. The metal frame is preferably formed of tubular members welded together, and except for the arms 4, is conventional.

To the lower peripheral surface of the cross-member 5 is welded a horizontal shaft 9, the opposite ends of which extend slightly beyond the cross-member.

The rock gouging element of the present invention includes a heavy rectangular body 10, made of solid steel, or other suitable material. The body has two spaced forwardly extending arms 11 and 12 formed integrally therewith, and each of the arms has an up-turned hook 13 formed on its extreme forward end. The arms are spaced apart a proper distance to permit their engagement with the two laterally projecting ends of the shaft 9.

The upper surface of each of the two arms is provided with a vertical shoulder 14, and a suitable detent 15 is adapted to seat against each shoulder, and to be held in place by bolts 16. The detents 15 are adapted to close the spaces between the hook points and the arms in an obvious manner, so as to hold the arms in pivotal engagement with the shaft 9.

The gouge body 10 has a plurality of spaced through perforations 17, which are polygonal in cross-section, and which are slightly tapered upwardly. Gouging bits 18 are adapted to be removably disposed in desired ones of the perforations 17.

The bits 18 are identical, and each consists of an upper shank 19 which is complementary in cross-section to the perforations 17, a surrounding stop-shoulder 20, and a tapered point portion 21 below the shoulder. The point portion 21 is bent slightly toward the tractor. The shank 19 is of sufficient length to pass upwardly through one of the perforations 17, and to project above the body 10. Removable pins 22 are adapted to be inserted through transverse perforations in the shanks in order to hold the bits in rigid engagement with the body 10.

As a means for pivotally swinging the body 10 vertically with relation to its pivotal axis (the shaft 9), the following described mechanism is provided.

The upper surface of the body 10 is equipped with two spaced upwardly projecting ears 23, each of which is provided with a transverse perforation 24. Pivotally connected to each of the ears 23 by a pivot pin 25 is the lower bifurcated end 26 of an upstanding piston rod 27.

The upper end of each of the piston rods 27

extends into the lower end of a hollow cylindrical piston chamber 28, and is equipped therein with a conventional piston head, not shown.

The upper end of each of the two piston chambers 28 has two upwardly projecting spaced ears 29. Each pair of the ears 29 embraces the rear end portion of one of the hereinabove described arms 4 on one of the posts (2 or 3), and a pivot pin 30 is provided to connect the ears and the arm.

A hose line 31 leads to the upper end of each of the piston chambers 28 from a seat of fluid supply, not shown, but which is adapted to deliver fluid under pressure to the piston chamber above the piston therein.

A second fluid conveying hose 32 leads to the lower end of each of the two piston chambers 28 from the fluid supply seat.

The two pistons may be simultaneously moved in a downward direction by simultaneous introduction of pressure fluid into the chambers through the upper hose lines 31. A suitable manually operated control valve, not shown, is provided in the plumbing connection of the hose lines 31 and 32 in order to selectively control fluid flow to the piston chambers either through the two lines 31 or the two lines 32 simultaneously therethrough.

The exposed lower portions of the two piston rods 27 may be surrounded by a suitable collapsible rubber envelope 33, if desired, in order to protect the piston rods against dirt.

Fluid pressure may be delivered into the piston chambers simultaneously below the piston heads therein, through the two lines 32. When so delivered, the gouge is raised.

The device is operated in an obvious manner by merely selectively controlling delivery of pressure fluid to the piston chambers.

It is pointed out that the present mechanism may be installed on conventional tractors without modifying them further than providing the arms 4 and welding the horizontal shaft 9 to the cross-member 5.

It is also pointed out that the arrangement is such that the device may be installed and oper-

ated without interfering with the usual winch mechanism of winch equipped tractors. The device does not interfere with the usual operation of the usual winch cable 36 over the usual roller 37 or operation of the usual winch drum 38.

It is pointed out that when the gouge bits 18 are thrust downwardly into the earth's surface, substantially the whole weight of the rear end of the tractor may be utilized to urge the bit points into the ground.

Obviously the invention is susceptible to some change or alteration without defeating its practicability, and I therefore do not wish to be confined to the preferred embodiment shown in the drawings and described herein, further than I am limited by the scope of the appended claims.

I claim:

1. In earth working equipment adapted to be drawn along the earth's surface by an automotive vehicle, the combination with a rigidly mounted laterally disposed horizontal draw-bar carried at one end of the vehicle, of: a laterally disposed horizontal tool carrying beam; forwardly projecting horizontal parallel arms carried by the beam; an upturned rearwardly open hook at the forward end of each arm, said hooks adapted to receive said draw-bar; and a keeper removably attached to each arm in position to retain the draw-bar in the hook.

2. Structure as specified in claim 1, in which the keeper includes a rigid metal block bolted to the arm; and a forwardly facing vertical shoulder in the upper face of the arm and against which the keeper is abutted.

CHARLES P. HALL.
